MACHINE FOR APPLYING PRESSURE TO
SOLES AND SHOESSidney J. Finn, Beverly, Mass., assignor to United
Shoe Machinery Corporation, Paterson, N. J.,
a corporation of New Jersey

Application January 6, 1938, Serial No. 183,674

17 Claims. (Cl. 12—33)

This invention relates to machines for applying pressure to soles and shoes and is illustrated herein as embodied in a machine for cement attaching soles to shoe bottoms.

5 In many cement sole attaching machines in use today the pressing devices or pad boxes in which the soles and shoes are placed to receive sole attaching or sole laying pressure are provided with sole and shoe positioning mechanisms operative 10 to position these members relatively to each other on a pressure applying or pressure sustaining pad in the pad box. These pads are usually fluid filled flexible chambers of rubber or similar material adapted either to be distorted by inflation 15 to apply pressure, or to be distorted by having the sole and shoe pressed forcibly against their shoe receiving walls. In either case, the sole and shoe and the flexible wall of the pad are moved relatively to each other during the pressure applying operation.

It will be apparent from the foregoing that when positioning mechanisms such as gages adapted to engage the opposite sides of a sole or shoe are utilized, there is a grave danger of damaging the shoe upper if these gages remain in contact with the sole or shoe while the shoe and pad are moved relatively to each other during the pressure applying operation. On the other hand, it is essential that the positioning gages 30 remain in operative engagement with the sole and shoe until at least sufficient pressure has been applied to prevent relative displacement of these members before the sole has become attached to the shoe bottom.

35 An object of the present invention is to provide improved means in a machine of the type referred to for withdrawing shoe positioning mechanism from engagement with the shoe during the pressure applying operation.

40 To the accomplishment of this object the invention provides, in combination with sole positioning gage mechanism and separate shoe positioning gage mechanism, improved means for withdrawing the shoe gage mechanism only from 45 operative position during the pressure applying operation. As herein illustrated, the gage withdrawing mechanism is constructed and arranged to be operated automatically after a predetermined pressure has been applied to the sole and 50 shoe, this pressure being sufficient to insure that the sole and shoe will not become displaced relatively to each other after the gages have been withdrawn or during the remainder of the pressure applying operation.

55 In the illustrated construction the sole gage

mechanism comprises a tongue for centralizing the sole widthwise of the pad and having a pin for engaging a hole on the longitudinal median line of the sole. The shoe gage mechanism comprises a pair of gage fingers interconnected for equal and opposite movement and actuated by the engagement of a projection thereon in a cam slot formed in a gage operating slide movable transversely of the pad relatively to the gages. The shoe gage withdrawing mechanism, as herein illustrated, is actuated by the operation of the pressure applying mechanism of the machine and the construction is such that the gage withdrawing mechanism maintains the gages withdrawn from engagement with the shoe until after 15 the pressure on the sole and shoe is relieved.

With the above and other objects and features in view the invention will now be described with reference to the accompanying drawings and will thereafter be pointed out in the claims.

In the drawings,

Fig. 1 is an elevational view of a portion of the machine embodying the present invention including a pad box and mechanism for applying pressure to a sole and shoe mounted therein, the view 25 being taken looking toward the heel end of the pad box;

Fig. 2 is a plan view of the gage withdrawing mechanism of the machine;

Fig. 3 is an elevational view, similar to Fig. 1 30 but on an enlarged scale, showing the pressure applying mechanism in an operated position;

Fig. 4 is a plan view of the heel portion of the pad box and the sole and shoe positioning mechanism carried thereby; and

Fig. 5 is a detail perspective view of a part of the gage withdrawing mechanism.

The invention is illustrated herein as embodied in a cement sole attaching machine of the type disclosed in Letters Patent of the United States 40 No. 2,047,185, granted July 14, 1936, on an application filed in the names of Milton H. Ballard et al. As disclosed in the patent referred to, the machine is provided with a rotary turret 10 (Fig. 1) having a plurality of radially projecting 45 shelves or brackets 12 upon which are mounted pad boxes 14 provided with sole and shoe receiving pads 15 (Fig. 4) against which a sole and shoe may be pressed to cause the sole to become attached to the shoe bottom. Each pad box 14 50 is provided with sole and shoe positioning mechanism at its forepart and rear portions for locating the sole and shoe relatively to each other on the pad. Since the present invention is concerned only with the positioning mechanism at 55

the rear or heel end of the pad box, the forepart of the box and the positioning mechanism thereon have not been disclosed. While the invention is illustrated herein with reference to a machine 5 and a pad box of the types referred to, it is to be understood that in its broader aspects the invention is not limited in its use to such constructions but may be applied to other types of pad boxes and cement sole attaching machines.

10 The mechanism for positioning the heel portion of a sole on the pad 15 is similar in construction and operation to that disclosed in the Ballard patent referred to and comprises a forwardly extending gage or tongue 16 (Fig. 4) pivotally mounted on the forward end of a short horizontal slide 18 and carrying at its forward end a short pin 20 which projects downwardly from the under side of the tongue and is adapted to engage a hole formed in the heel portion of a sole, this hole being usually located on the longitudinal median line of the sole. The tongue 16 is pivoted on the slide 18 by a pin 22 and is arranged to swing heightwise of the pad within predetermined limits to permit the sole to be placed in position to be engaged by the pin 20. A toggle spring 24 extending between the slide and the tongue acts to maintain the latter in either its operative position against the pad or its inoperative position raised from the pad.

15 20 The horizontal slide 18 is mounted in a T-slot 26 (Fig. 1) extending lengthwise of the pad in a casting 28 secured to gage supporting mechanism 29 of substantially the same construction as that disclosed in United States Letters Patent No. 35 2,005,755, granted June 25, 1935, on an application filed in the name of Francis J. Better. As disclosed in the Better patent, the sole and shoe positioning mechanism at the heel end of the pad box is carried by a vertical slide 30 mounted 40 in guideways formed in the right-hand end of the pad box, this slide having a rearwardly extending horizontal bracket 32 at its upper end for supporting the heel end positioning mechanism. Since the construction and operation of this supporting mechanism, including means for adjusting the positioning mechanism as a unit longitudinally of the pad box, and also means whereby the entire assembly may be adjusted angularly about a horizontal pivot to position 45 50 the gage mechanism relatively to the top surface of the pad, is fully disclosed in the Better patent, no further description of this mechanism will be given herein and reference may be had to the patent mentioned for a more complete disclosure thereof.

55 The slide 18 and heel gage or tongue 16 are normally held in a forward position in the slot 26 by a spring 34 (Fig. 4) engaging a pin 36 on the slide and mounted on a pin 38 projecting downwardly from an upper casting 40 which, together with the casting 28, is fastened to the gage supporting mechanism 29 by screws 42. When the operator positions the heel portion of a sole A 60 on the pad, he moves the tongue 16 rearwardly 65 of the pad box against the spring 34 and inserts the pin 20 in the hole in the heel end of the sole, the forepart of the sole, as is customary in this type of pad box, being thereafter positioned by the forepart sole and shoe positioning mechanism. After positioning the forepart of the sole the operator releases the gage 16 and the spring 34 acts to hold the gage forwardly under light tension and thereby prevents the sole from moving rearwardly out of contact with the forepart 70 gages. If desirable, the tension of the spring 34

may be sufficient to cause the shank portion of the sole to buckle slightly away from the pad so that when a shoe B on a last L is placed on the pad, the shank portion of the sole will always engage the shank portion of the shoe before 5 pressure is applied, even though the initial conformation of the pad may not be such as to insure this result in all cases. Since the castings 28 and 40 are fastened by the screws 42 to the gage supporting mechanism 29, the slide 18 and 10 gage 16 are fixed against movement widthwise of the pad, the position of these members being such that the pin 20 will centralize the heel portion of the sole widthwise of the pad.

The casting 28 is provided on its lower side with a transverse slot 44 (Fig. 4) in which is mounted a slide member 46. Pivoted on the slide member 46 on pins 48 are a pair of shoe engaging fingers or gages 50 which are interconnected for equal movement in opposite directions by intermeshing gear segments 52, this construction being substantially the same as the arrangement of the shoe engaging fingers of the Better patent referred to. Mounted for transverse sliding movement in a slot 54 in the upper casting 40 is another slide 56 provided with an inclined cam slot 58 into which projects a roll 60 mounted on a laterally extending portion of one of the gage fingers 50. Transverse sliding movement of the slide 56 toward or away from the operator will cause the roll 60 to be moved forwardly or rearwardly of the pad by its engagement with the cam slot 58 and thereby move the interconnected fingers 50 toward or away from the shoe B on the pad. The shoe gages or fingers 50 may be 35 adjusted transversely of the pad relatively to the sole gage 16 by an eccentric adjustment 62 mounted on the casting 28 and operating on the transverse slide 46, this adjusting mechanism being arranged to be maintained by friction in 40 any position into which it may be moved, as fully disclosed in the Better patent.

A cement sole attaching machine of the type embodying the present invention is provided with pressure applying members or abutments for engaging the forepart of the shoe and the top of the heel portion of the last in the shoe and pressing the shoe and sole forcibly against the pad to apply the sole attaching or sole laying pressure. As illustrated in the Ballard et al. patent referred to, these abutments consist of a last engaging abutment 64 (Fig. 3) and a shoe engaging abutment (not shown) adjustably mounted in vertically movable brackets carried by a swinging frame member 66. The bracket for supporting the heel engaging abutment 64 comprises an upwardly and forwardly curved arm 68 pinned to a vertically movable shaft 70 which is normally supported in its uppermost position in the machine by a spring 72. The shaft 70, bracket 68 and abutment 64 are moved downwardly relatively to the swinging frame 66 by a pressure applying lever 74 engaging the forward end of the bracket 68 and pivoted on a shaft 76 in the swinging frame. The lever 74 (and a corresponding lever which operates the forepart shoe engaging abutment) have rearwardly extending arms 78 which are engaged by the opposite ends of a pivoted lever 80 extending between the pressure applying levers and pivoted in a manner to cause 70 the pressure of these levers against the abutments to be substantially equalized. As disclosed in the Ballard et al. patent, the pressure applying mechanism of the machine comprises fluid pressure operated means which acts upon 75

the pivoted lever 80 when the operator treads the machine, the part of this mechanism associated with the portion of the machine illustrated in Fig. 1 being indicated generally in that figure by the numeral 82. Since this fluid pressure applying mechanism is relatively complicated and is fully disclosed in the Ballard et al. patent, no further description thereof will be given herein.

10 The swinging frame member 66 is arranged to be swung by a handle 83 (Fig. 1) from a rearwardly inclined position, in which the pressure applying abutments are removed from over the pad, into a substantially vertical position, as shown in Figs. 1 and 3, in which the forepart abutment referred to and the last engaging abutment 64 are located over the shoe and in position to be moved downwardly by the pressure applying levers 78 to apply pressure to the sole 15 and shoe. This forward swinging movement of the swinging frame 66 is utilized to move the heel end shoe positioning mechanism into operative engagement with the shoe. This is accomplished by connecting the transverse slide 56 to 20 a pivoted lever 84 (Fig. 3) by a rod 86 having universal connections 88 and 90 with the slide 56 and the lever 84, respectively, the lever 84 being pivoted for free swinging movement on the shaft 76 in the swinging frame 66. In order that 25 the pivoted lever 84 will move the slide 56 forwardly toward the operator to operate the shoe gages 50 during the forward swinging movement of the swinging frame, the pivoted lever is provided with a rearwardly extending projection 92 30 having a notch 94 therein which is arranged to be engaged by a detent 96 on a rearwardly extending arm of a lever 98 pivoted at 100 on the swinging frame 66 and normally urged upwardly toward the notch 94 by a spring 102 connected to 35 the lever 98 and to the swinging frame. The construction is such that when the swinging frame is in its rearwardly inclined, inoperative position the detent 96 engages the notch 94. This causes the lever 84 to move the slide 56 outwardly toward the operator as the swinging frame 66 moves forwardly thus moving the gage fingers 50 inwardly toward each other until they engage the opposite sides of the heel portion of the shoe. Upon engagement of the gage fingers with the shoe, the lever 84 becomes disengaged from the 40 detent 96 and, because of the contact of the gages 50 with the shoe, remains in a stationary position during the remainder of the forward swinging movement of the swinging frame. In this 45 way the gages are brought inwardly against the shoe and are maintained in engagement therewith during the application of some pressure thereto. The angle of the slot 58 in the slide 56 is such that the gages are locked against movement away from the shoe after they have contacted therewith. As disclosed in the Better patent referred to, a tension spring 104, connected at one end to the transverse slide 56 and at its other end to the casting 40, causes the 50 gage fingers 50 to move yieldingly further toward each other and the shoe in case the shoe should move slightly on the sole after the lever 84 has become disconnected from the detent 96, thereby insuring that the gages will always contact with the shoe during the positioning operation.

As indicated above, it is desirable, after a predetermined preliminary pressure has been applied to the sole and shoe, for example, a pressure of twenty or thirty pounds which is sufficient to prevent these members from becoming displaced

5 relatively to each other before the full pressure has been applied, to withdraw the gage fingers 50 from engagement with the opposite sides of the shoe so that, as the shoe is sunk further into the pad by the pressure applying mechanism, there will be no danger of scarring or otherwise injuring the shoe upper through the engagement therewith of the shoe positioning gages or fingers during this downward movement. Accordingly, 10 in order to effect withdrawal of the gage fingers 50 automatically after a predetermined pressure has been applied to the sole and shoe, the following mechanism has been provided.

The last engaging abutment 64 has a shank or stem 106 (Fig. 3) which is supported for 15 sliding movement heightwise of the pad in a carrier member 108 mounted for adjustment lengthwise of the pad in a T-slot 110 formed in the forward end of the bracket 68. At opposite sides of the stem 106 the member 108 carries in 20 appropriate openings a pair of compression springs 112 (Figs. 1 and 2), the lower ends of which bear against the abutment 64 and press it downwardly with a pressure determined by the size of the springs. Although this pressure can 25 be varied it is preferably about twenty pounds to the square inch. The abutment 64 is retained in position in the carrier member by a pin 114 which enters a vertical slot (Fig. 3) in the stem 106 and thus prevents the abutment from dropping 30 out of the carrier member or from turning therein. By this arrangement the abutment may yield a limited amount relatively to the carrier member and bracket 68 during the first part of the pressure applying action or until the 35 upper surface of the abutment contacts with the carrier member at which time, as indicated above, the pressure on the shoe will preferably be about twenty pounds to the square inch over its bottom area.

40 The abutment 64 has a portion extending inwardly from the operator, as best shown in Figs. 1 and 3, and this inner portion is engaged by a vertical pin 116 slidably mounted in the bracket 68. The bracket 68 has a laterally and upwardly 45 extending portion 118 formed thereon which supports the handle 83. The upper end of the sliding pin 116 engages the outer end of a substantially horizontal lever 120 pivoted at 122 on the bracket 68 and held against the pin by a spring 50 123 (Fig. 2). The lever 120 (Fig. 3) has an inwardly extending arm pivotally connected by a pin 124 to an upwardly extending link 126, the upper end of which is provided with a slot 128. The portion 118 of the bracket 68 has an upwardly 55 projecting cylindrical portion 130 in which is mounted for vertical sliding movement a shaft 132 provided on its outer side with ratchet teeth 134. The lower end of the shaft 132 carries a pin 136 which is engaged in slots 138 formed in 60 a pair of ears on an outwardly extending arm 140 integral with the pivoted lever 84.

65 Adjacent to the vertical shaft 132 and pivoted on a pin 142 is a pawl 144. The pawl has an arm carrying a pin 146 which rides in the slot 128 in the vertical link 126. The pawl is normally urged in a counterclockwise direction, as viewed in Figs. 1 and 3, to move it into engagement with the ratchet teeth 134 by a spring 148 connected to the pawl and to the portion 118 of 70 the bracket 68.

75 When the mechanism is in the position shown in Fig. 1, the pin 146 of the pawl bears against the lower end of the slot 128 and the pawl is thus held out of engagement with the ratchet teeth on the 75

shaft 132 so that the latter is free to slide heightwise in the portion 130 of the bracket 68. After the sole and shoe have been relatively positioned on the pad and the treadle of the machine has been operated to cause the pressure to be applied to the shoe, the two levers 78 move the brackets 68 carrying the shoe and the last engaging abutments downwardly against the springs 72, as explained above. The last engaging abutment 64 yields upon engagement with the last against the springs 112 until the upper surface of the abutment contacts with the carrying member 108. This action moves the pin 116 upwardly to cause the lever 120 to swing in a clockwise direction, as viewed in Fig. 3, about its pivot 122 to lower the vertical link 126 and thereby free the pin 146 in the pawl 144 so that the spring 148 can swing the latter into locking engagement with the ratchet teeth on the shaft 132. It will be seen from the above that during the first part of the downward movement of the castings 68 and the last and shoe engaging abutments, the shaft 132 does not move downwardly owing to its connection with the arm 140 of the pivoted lever 84 which, it will be recalled, is held stationary due to the contact of the shoe gages or fingers 50 with the opposite sides of the shoe. The abutments will apply a predetermined pressure to the sole and shoe during this downward movement depending upon the strength or resistance of the springs 112 acting on the last engaging abutment 64. After the pawl 144 has been moved into engagement with the ratchet teeth on the shaft 132, the latter becomes locked to the downwardly moving bracket 68 and the portion 130 thereof and consequently moves downwardly with it as a unit during the remainder of the pressure applying operation. Downward movement of the shaft 132 swings the arm 140 and the pivoted lever 84 in a counterclockwise direction, as viewed in Fig. 3, to move the rod 86 and the transverse slide 56 inwardly away from the operator and thereby to cause the gage fingers 50 to move out of the operative position shown in broken lines in Fig. 4 into the open position shown in full lines in that figure. Consequently, the gage fingers 50 are withdrawn from operative or shoe engaging position to a retracted or inoperative position and are maintained in such retracted position during the remainder of the pressure applying operation.

After the pressure applying operation has been completed the abutment 64 and its supporting bracket 68 are permitted by the pressure applying lever 78 to be moved upwardly by the spring 72 away from the last and shoe. This permits the abutment 64 to return to its initial lower position relatively to the member 108 which, through the mechanism already described, causes the pawl 144 to be withdrawn from engagement with the shaft 132, thereby permitting the latter to be moved upwardly by contraction of the spring 104 on the transverse slide 56 so that the shoe gages 50 move inwardly again into engagement with the shoe.

After pressure has been relieved on the sole and shoe, the swinging frame 66 returns automatically to its rearwardly inclined, inoperative position. This swinging action of the frame member 66 moves the pivoted lever 84 about its pivot into a position that permits the detent 96 to become engaged again in the notch 94 and thereby connect the pivoted lever with the transverse slide 56 and the shoe gages operated thereby. Consequently, the remainder of the rear-

ward swinging movement of the swinging frame causes the shoe gage fingers 50 to be retracted positively by the gage operating mechanism into their open or inoperative position. The shoe B with its sole A cement attached thereto throughout the forepart and shank portions of the shoe bottom may now be lifted from the pad and the pin 20 on the gage 16 disengaged from the hole in the heel end of the sole. A fresh sole may then be mounted on the pad and positioned as described above prior to its attachment to a shoe.

Having thus described my invention, what I claim as new and desire to secure by Letters Patent of the United States is:

1. A machine for applying pressure to soles and shoes having, in combination, a pad for receiving a sole and shoe, gage mechanism for positioning the sole on the pad, separate gage mechanism for positioning the shoe relatively to the sole, and means for withdrawing the shoe gage mechanism only from operative position during the pressure applying operation.

2. A machine for applying pressure to soles and shoes having, in combination, a pad for receiving a sole and shoe, gage mechanism for positioning the sole on the pad, separate gage mechanism for positioning the shoe relatively to the sole, and means for automatically withdrawing the shoe gage mechanism only from operative engagement with the shoe after a predetermined pressure has been applied to the sole and shoe.

3. A machine for applying pressure to soles and shoes having, in combination, a pad for receiving a sole and shoe, gage mechanism for positioning the sole on the pad, separate gage mechanism for positioning the shoe relatively to the sole, means for applying pressure to the sole and shoe, and means actuated by the operation of said pressure applying means for withdrawing the shoe gage mechanism only from engagement with the shoe.

4. A machine for applying pressure to soles and shoes having, in combination, a pad for receiving a sole and shoe, gage mechanism for positioning the heel portion of the sole on the pad, separate gage mechanism for positioning the heel portion of the shoe relatively to the sole, and means for withdrawing the shoe heel gage mechanism only from operative position during the pressure applying operation.

5. A machine for applying pressure to soles and shoes having, in combination, a pad for receiving a sole and shoe, gage mechanism for positioning the heel portion of the sole on the pad, separate gage mechanism for engaging the opposite sides of the heel portion of the shoe and positioning the shoe relatively to the sole, and means for automatically moving the shoe gage mechanism only out of engagement with the opposite sides of the shoe before the full pressure has been applied to the sole and shoe.

6. A machine for applying pressure to soles and shoes having, in combination, a pad for receiving a sole and shoe, gage mechanism for positioning the heel portion of the sole on the pad, separate gage mechanism for positioning the heel portion of the shoe relatively to the sole, and means actuated by the application of pressure to the sole and shoe for withdrawing the shoe gage mechanism only from operative engagement with the shoe while pressure is being applied thereto.

7. A machine for applying pressure to soles and shoes having, in combination, a pad for receiving a sole and shoe, gage mechanism for

positioning the heel portion of the sole on the pad, separate gage mechanism for positioning the heel portion of the shoe relatively to the sole, and means for automatically withdrawing the shoe heel gage mechanism only from operative position after a predetermined pressure has been applied to the sole and shoe.

8. A machine for applying pressure to soles and shoes having, in combination, a pad for receiving a sole and shoe, gage mechanism for positioning a sole on the pad, separate gage mechanism for positioning a shoe on the sole, and means for withdrawing only the shoe gage mechanism from operative position while pressure is being applied to the sole and shoe, said means being arranged to maintain said gage mechanism in its withdrawn position until after pressure on the sole and shoe is relieved.

9. A machine for applying pressure to soles and shoes having in combination, a pad for receiving a sole and shoe, a single gage for positioning the heel portion of the sole on the pad, a pair of gages for positioning the heel portion of the shoe relatively to the sole, means for applying pressure to the sole and shoe, and means actuated by operation of said pressure applying means for automatically withdrawing said pair of shoe gages from engagement with the shoe.

10. A machine for applying pressure to soles and shoes having, in combination, a pad for receiving a sole and shoe, a gage for positioning the heel portion of the sole on the pad, a pair of gages for positioning the heel portion of the shoe relatively to the sole, means for actuating said shoe gages to move them yieldingly into operative engagement with the shoe, and separate means for causing the shoe gage operating means to withdraw said shoe gages positively from engagement with the shoe during the application of pressure thereto.

11. A machine for applying pressure to soles and shoes having, in combination, a pad for receiving a sole and shoe, gage mechanism for positioning the heel portion of the sole on the pad, separate gage mechanism for positioning the heel portion of the shoe on the sole, means for actuating the shoe gage mechanism to position the shoe on the sole, means for applying pressure to the sole and shoe, and means actuated by operation of said pressure applying means for automatically withdrawing the shoe gage mechanism from engagement with the shoe after a predetermined pressure has been applied to the sole and shoe.

12. A machine for applying pressure to soles and shoes having, in combination, a pad for receiving a sole and shoe, gage mechanism for positioning the heel portion of the sole on the pad, a pair of gages for positioning the heel portion of the shoe relatively to the sole, means for actuating said shoe gages, said means including a swinging member movable laterally of the pad into and out of operative position and connections between said swinging member and said shoe gages for actuating said gages as said member moves into operative position, and means operated by the application of pressure to the sole and shoe for causing said connections to withdraw the shoe gages from the shoe while said swinging member is still in its operative position.

13. A machine for applying pressure to soles and shoes having, in combination, a pad for receiving a sole and shoe, a gage for positioning the heel portion of the sole on the pad, a pair

of gages for positioning the heel portion of the shoe on the sole, means for applying pressure to the sole and shoe including a swinging member movable transversely of the pad from a rearwardly inclined inoperative position into a substantially vertical operative position, said swinging member carrying abutments for engaging and applying pressure to the last and shoe, means carried by said swinging member for actuating the shoe gages, and means also carried by said swinging member and actuated by the pressing of said abutments against the last and shoe for moving said shoe gage actuating means toward its inoperative position while the swinging member is still in its vertical position, thereby positively withdrawing said shoe gages away from engagement with the shoe during the application of pressure thereto and holding said gages in their withdrawn position during the remainder of the pressure applying operation.

14. A machine for applying pressure to soles and shoes having, in combination, a pad for receiving a sole and shoe, gages for positioning the sole on the pad, gages for positioning the shoe relatively to the sole, an abutment for applying pressure to the sole and shoe, said abutment being arranged for limited yielding movement during its pressure applying action, and means actuated by the yielding movement of said abutment for moving the shoe gages only away from engagement with the shoe.

15. A machine for applying pressure to soles and shoes having, in combination, a pad for receiving a sole and shoe, a gage for positioning the sole on the pad, gages for positioning the shoe relatively to the sole, an abutment for applying pressure to press the sole and shoe against the pad, said abutment being arranged for limited yielding movement heightwise of the pad during the pressure applying operation, and means actuated by said limited yielding movement of the abutment for withdrawing the shoe gages only from operative position before the full pressure has been applied to the sole and shoe, said means acting also to hold said shoe gages in their withdrawn position until after pressure on the sole and shoe is relieved.

16. A machine for applying pressure to soles and shoes having, in combination, a pad for receiving a sole and shoe, a gage for positioning the heel portion of the sole on the pad, a separate pair of gages for engaging the opposite sides of the heel portion of the shoe and positioning said portion relatively to the sole, an abutment for pressing the sole and shoe against the pad, means for supporting said abutment for yielding movement heightwise of the pad during its pressing action and after it has applied a predetermined pressure to the sole and shoe, and means actuated by the yielding movement of said abutment for automatically retracting the shoe gages only from their engagement with the shoe before the full pressure has been applied thereto.

17. A machine for applying pressure to soles and shoes having, in combination, a pad for receiving a sole and shoe, a pin for engaging a hole in the heel portion of the sole and centralizing said portion widthwise of the pad, a pair of equally and oppositely movable gages for positioning the heel portion of the shoe relatively to the sole, a member arranged for swinging movement widthwise of the pad, an abutment carried by the swinging member for applying pressure to the sole and shoe, said abutment being arranged for limited yielding movement heightwise of the

pad during its pressure applying action, a lever pivoted on said swinging member, connections between said pivoted lever and the shoe gages for operating said gages when the swinging member is swung into operative position, and means between said lever and said abutment and actuated by the yielding action of said abutment during its pressure applying action for operating said

pivoted lever to withdraw the shoe gages from engagement with the shoe after a predetermined pressure has been applied thereto, said means comprising a slidable shaft connected to said pivoted lever and held against sliding movement by a pawl, and mechanism for automatically withdrawing said pawl.

SIDNEY J. FINN.
